CLAIM

The ornamental design for a food processing cooker, as shown and described.

DESCRIPTION

The patent or application file contains at least one drawing executed in color. Copies of this patent or patent application publication with color drawing(s) will be provided by the Office upon request and payment of the necessary fee.

1. Food processing cooker

1.1: Front

1.2: Back

1.3: Left

1.4: Right

1.5: Top

1.6: Bottom

1.7: Perspective

The portions of the design shown in red color are for the purpose of illustrating portions of the food processing cooker and form no part of the claimed design.

1 Claim, 7 Drawing Sheets
